DESIGN FOR A BOWL FOR FLOWERS OR THE LIKE

Nancy L. Wade, Los Angeles, Calif.

Application May 22, 1944, Serial No. 113,713

Term of patent 14 years

(Cl. D44—15)

To all whom it may concern:

Be it known that I, Nancy L. Wade, a citizen of the United States, residing at Los Angeles, in the county of Los Angeles and State of California, have invented a new, original, and ornamental Design for a Bowl for Flowers or the like, of which the following is a specification, reference being had to the accompanying drawing, forming part thereof.

Figure 1 is a perspective view of the bowl, for flowers or the like, showing my new design;

The hatched areas denote portions whose color contrasts with the plan portions of the article.

I claim:

The ornamental design for a bowl for flowers or the like, as shown and described.

NANCY L. WADE.
